BARRETTE OR THE LIKE

Morris H. Todfield, Brooklyn, N. Y., assignor to Delamere Company, Inc., a corporation of Delaware

Application July 6, 1950, Serial No. 10,968

Term of patent 7 years

(Cl. D86—10)

To all whom it may concern:

Be it known that I, Morris H. Todfield, a citizen of the United States, residing in the Borough of Brooklyn, city of New York, county of Kings, and State of New York, have invented a new, original, and ornamental Design for a Barrette or the like, of which the following is a specification, reference being had to the accompanying drawings, forming a part thereof, in which:

Fig. 1 is a front elevation or face view of a barrette, showing my new design; and

Fig. 2 is a top plan view.

The characteristic features of the design are shown in full lines.

I claim:

The ornamental design for a barrette or the like, substantially as shown and described.

MORRIS H. TODFIELD.
